Attn:

UNITED STATES PATENT OFFICE

170,981

PAIR OF BINOCULARS

David Kane, San Antonio, Tex.

Application August 31, 1953, Serial No. 26,631

Term of patent 14 years

(Cl. D57—1)

To all whom it may concern:

Be it known that I, David Kane, a citizen of the United States, and a resident of the city of San Antonio, in the county of Bexar and State of Texas, have invented a new, original, and ornamental Design for a Pair of Binoculars, of which the following is a specification, reference being had to the accompanying drawing forming a part thereof.

On the drawing:

Figure 1 is a front elevational view of a pair of binoculars, showing my new design;

Figure 2 is a side elevational view;

Figure 3 is a bottom plan view; and

Figure 4 is a top plan view thereof.

I claim:

The ornamental design for a pair of binoculars, as shown.

DAVID KANE.
